(57) **CLAIM**

The ornamental design for an irrigation device assembly, as shown and described.

DESCRIPTION

FIG. 1 is an exploded front elevation view of an irrigation device assembly, including a bottle, a backsplash shield with centralized nozzles, and a gasket therebetween.

FIG. 2 is a right side elevation view of a bottle of the irrigation device assembly. The left side view is a mirror image thereof.

FIG. 3 is a front elevation view of a bottle of the irrigation device assembly. The back elevation view is a mirror image thereof.

FIG. 4 is a top plan view of a bottle of the irrigation device assembly.

FIG. 5 is a bottom plan view of a bottle of the irrigation device assembly.

FIG. 6 bottom plan view of a backsplash shield of the irrigation device assembly.

FIG. 7 is top plan view of a backsplash shield of the irrigation device assembly.

FIG. 8 is a front side elevation view of a backsplash shield of the irrigation device assembly. The back side elevation view is a mirror image thereof.

FIG. 9 is a right side elevation view of a backsplash shield of the irrigation device assembly. The left side elevation view is a mirror image thereof.

FIG. 10 is a sectional view of the backsplash shield shown in FIG. 8 taken along line 10—10.

FIG. 11 is a top plan view of a washer of the irrigation device assembly. The bottom plan view is a mirror image thereof.

FIG. 12 is a front elevation view of a gasket of the irrigation device assembly. The back elevation view is a mirror image thereof.

FIG. 13 is an exploded front elevation view of an alternative design embodiment of an irrigation device assembly, including a bottle and backsplash shield with centralized nozzles.

FIG. 14 is a right side elevation view of a bottle of the alternative design embodiment of the irrigation device assembly. The left side view is a mirror image thereof.

FIG. 15 is a front elevation view of a bottle of the alternative design embodiment of the irrigation device assembly. The back elevation view is a mirror image thereof.

FIG. 16 is a top plan view of a bottle of the alternative design embodiment of the irrigation device assembly.

FIG. 17 is a bottom plan view of a bottle of the alternative design embodiment of the irrigation device assembly.

FIG. 18 bottom plan view of a backsplash shield of the alternative design embodiment of the irrigation device assembly.

FIG. 19 is top plan view of a backsplash shield of the alternative design embodiment of the irrigation device assembly.

FIG. 20 is a front side elevation view of a backsplash shield of the alternative design embodiment of the irrigation device assembly. The back side elevation view is a mirror image thereof.

FIG. 21 is a right side elevation view of a backsplash shield of the alternative design embodiment of the irrigation device assembly. The left side elevation view is a mirror image thereof; and,

FIG. 22 is a sectional view of the backsplash shield shown in FIG. 20 taken along line 22—22.

The features shown in broken lines depict environmental subject matter only and form no part of the claimed design.
